Application June 21, 1954, Serial No. 438,016

4 Claims. (Cl. 37—117.5)

This invention relates generally to front end loaders, and more specifically to an improved loader capable of positive and efficient digging throughout a wide range at, above, and below the level of the loader, carrying, high and low level dumping, back filling, bulldozing and spreading of any materials commonly worked by a front end loader.

Many loaders are known in the present state of the art which are so arranged as to positively and efficiently perform the functions of digging, carrying and dumping. However, as the front end loader has become a more widely used machine, it has become necessary that the loader perform additional functions. Further these additional functions must be performed without affecting the digging, carrying and dumping qualities of the loader.

Specifically, it is an object of the present invention to provide a front end loader arrangement which will not only positively and efficiently dig, carry, bulldoze and dump, but will also positively and efficiently perform the functions of back filling and spreading. Some loaders in the prior art have been capable of back filling and spreading in addition to the standard functions. However, this has been done with the positioning of the cutting edge of the bucket in the dig position. This has resulted in extremely poor back filling and spreading, mainly for the reason that the cutting edge of the bucket tends to bite downward into the material. Thus spreading is either practically impossible or results in a spread of the material having a washboard effect.

It is a further object of the present invention to provide a front end loader which in addition to the enumerated functions, will also permit digging below the level of the prime mover.

It is a feature of the present invention that the bucket of the loader is always under the positive control of the loader operator.

Other objects and features of the present invention will be apparent upon a perusal of the following specification and drawings of which:

Figure 1 is a top plan view of a loader constructed according to the present invention;

Figure 2 is a side plan view of the loader shown in Figure 1 with the bucket in the dig position and showing, in dotted lines, the bucket in one carrying or tipped-back position;

Figure 3 is a side plan view of the invention with the bucket shown in the high lift carrying position and with the bucket shown in the dig position below the level of the prime mover or tractor in dotted lines; and

Figure 4 is a side plan view with the bucket shown in the back filling or spreading position and with the bucket shown in the high lift dump position in dotted lines.

The present embodiment is the preferred embodiment but it is to be understood that changes can be made in the present embodiment by one skilled in the art without departing from the spirit and scope of this invention.

Generally, the invention comprises a tractor 10 having a bucket 11 pivotally mounted on the forward end

of a boom 12, which is in turn pivotally mounted to the tractor, and link means 13 and 14 cooperating with the bucket 11 and the boom 12. A hydraulic ram 15 is provided for operation of the boom 12, and a hydraulic ram 16 is provided for operation of the link means.

The boom 12, the link means 13 and 14, and the hydraulic rams 16 and 15 are formed in duplicate and are disposed with one set on each side of the tractor 10.

Turning next to a detailed description of the present invention reference is made to the drawings. The prime mover or tractor 10 may be of any type well known in the art. However, in the present embodiment, the tractor 10 is shown as comprising a track laying type having a continuous track mechanism 17, which is shown diagrammatically. The tractor is provided with a hydraulic pump unit 18 which is suitably controlled by means (not shown) in the operator's compartment. The hydraulic pump unit 18 may be of any type well known in the art and is interconnected with the hydraulic rams 15 and 16 by lengths of tubing (not shown).

A supporting frame 19 is mounted on the track frame of the tractor at each side of the tractor 10, the supporting frame 19 substantially extends to the height of the top of the tractor 10. The boom 12, which comprises two identical members disposed on each side of the tractor between the track mechanism 17 and the tractor 10 is pivotally mounted to the supporting frame 19 by means of pivotal mounting means 20 substantially at the forward top edge thereof. The boom 12 is slightly bowed in a downward direction and is provided with an L-shaped mounting bracket 21. The L-shaped mounting bracket 21 is positioned substantially at the center of the boom 12 and is rigidly attached thereto. The other or lower end of the boom 12 is pivotally mounted to the bucket 11. The bucket 11 may be of any type well known in the art and is provided with a flange 22 in two sections on the rear thereof. The two sections of the flange 22 are spaced apart as can easily be seen in Figure 1, and the two sections are further disposed in a generally vertical direction. The boom 12 is pivotally mounted to the lower edge of the flange 22 by means of mounting means 23. It can thus be seen that the bucket 11 is pivotable about the mounting means 23 at the end of the boom 12 to a tipped back position for carrying a load of material, to a forwardly tipped position for dumping the bucket 11, and to an intermediate position for digging material with the bucket 11. The hydraulic ram 15, which is provided for raising and lowering of the boom 12, is formed in duplicate and is pivotally mounted at the rear thereof to the supporting frame 19. The piston of the hydraulic ram 15 is pivotally connected to one end of the L-shaped mounting bracket 21 by means of mounting means 24. Thus as the ram 15 is extended, the boom 12 is pivoted upwardly about mounting means 20, and as the hydraulic ram 15 is contracted, the boom 12 is pivoted downwardly about the mounting means 20.

To control the pivoting of the bucket 11 about the end of the boom 12, the link means 13 and 14 and the hydraulic ram 16 are provided. The link means 14 comprises a link arm which is pivotally mounted at one end to the flange 22 by means of the mounting means 25. The link means 13 comprises a lever arm which is pivotally mounted to the upper forward end of the mounting bracket 21 by means of mounting means 26. The other end of the lever arm and the other end of the link arm of the link means 13 and 14 are pivotally interconnected by means of mounting means 27. The hydraulic ram 16 is pivotally connected at one end thereof to the supporting frame 19 substantially at the top thereof by means of mounting means 28 as can easily be seen in the drawings. The mounting means 20 for the boom

12, and the mounting means 28 for the ram 16 are horizontally and vertically displaced from each other, the horizontal displacement being substantially larger than the vertical displacement, and with the mounting means 28 being disposed rearwardly and upwardly of the mounting means 20. The piston of the hydraulic ram 16 is pivotally connected to the lever arm of the link means 13 intermediate the ends thereof by means of mounting means 29. The L-shaped mounting bracket 21 is formed to have a slot therethrough along the width of the boom 12. This slot is of a width sufficient to permit the projection of the piston of the hydraulic ram 16 therethrough. Thus it may be seen that as the hydraulic ram 16 is extended, the lever arm of the link means 13 is pivoted in a counterclockwise direction as viewed in Figure 2 about the mounting means 26. The lower end of this lever arm will then move link means 14 to cause a pivoting of the bucket 11 about the mounting means 23 in a clockwise direction as viewed in Figure 2. A contraction of the hydraulic ram 16 will cause an opposite movement of these elements, in other words, the link means 13 will be pivoted in a clockwise direction, and the bucket 11 will be pivoted in a counterclockwise direction, as viewed in Figure 2.

The relative displacements of the various elements and the relative lengths of these elements may best be shown by a detailed description of the operation of the present invention. For this reason reference is again made to the drawings and firstly to Figure 2. Figure 2 shows the loader in the digging position at ground level and in dotted lines, one carrying position. In the digging position at ground level it may be noted that the cutting edge of the bucket 11 is disposed in a substantially horizontal plane at ground level. The hydraulic ram 15 is substantially contracted, as is the hydraulic ram 16. The boom 12 is then disposed at some point short of its lowermost position. The link means 13 is disposed at a small angle to the L-shaped bracket 21. The operator may, in this position, make upward and downward adjustments of the cutting edge of the bucket 11 by extending or contracting the ram 16. The bucket 11 may be tipped back from this digging position through an angle of approximately 40° by a substantially complete contraction of the hydraulic ram 16. When this is done, the bucket 11 and the link means 13 and 14 will assume the position shown in the dotted lines in Figure 2. This tip back of 40° is entirely sufficient for purposes of carrying a full load in the bucket 11.

If it is necessary to dig with the bucket 11 below ground level, the hydraulic ram 15 is caused to substantially completely contract as shown in the dotted lines in Figure 3. This will result in a slight tip back of the bucket 11 which is compensated for by a slight extension of the hydraulic ram 16. The bucket 11 may also be tipped back to a carrying position from this position. However, since the angle between the lower portion of the boom 12 and the flange 22 is less when the bucket 11 is below ground level, the maximum tilt back from this position is approximately 35°.

When the bucket 11 is in the tipped back or carrying position as shown in the dotted lines in Figure 2, or from the tipped back position from the digging position shown in dotted lines in Figure 3, the bucket may be raised through a relatively large arc to a high lift carrying position such as shown in Figure 3. This is accomplished by substantially completely extending the hydraulic ram 15, while the hydraulic ram 16 remains substantially completely contracted. Due to the horizontal component of displacement between the mounting means 28 and 29, there is a further tip back of the bucket 11 as the bucket 11 is raised from ground level to a position just below the eye level of the loader operator. As the bucket 11 is further raised beyond the eye level of the loader operator there is a slight automatic piv-

oting of the bucket 11 toward the dump position. This is advantageous in that the loader may be moved with the bucket 11 in the carrying position below the eye level of the loader operator without any spillage of the material over the forward cutting edge of the bucket 11, and further, as the boom 12 is raised to the high lift position no material will spill over the rear portion of the bucket 11 onto the tractor.

To dump the bucket 11 when the boom 12 is in the high lift position as shown in Figure 3, it is merely necessary to extend the hydraulic ram 16. Now this will cause a counterclockwise pivoting, as viewed in Figure 3, of the link means 13 about the mounting means 26, with a consequent movement of the link means 14 to in turn cause the bucket 11 to be pivoted in a clockwise direction as viewed in Figure 3 about mounting means 23 to the dump position as shown in Figure 4. From the high lift dump position, the bucket 11 may be easily returned to the dig position by a contraction of the hydraulic rams 15 and 16.

After the bucket 11 has been dumped, for instance preparatory to spreading the material, the loader may be placed in the spreading position by a contraction of the hydraulic ram 15 with the hydraulic ram 16 substantially expanded. The invention will then assume the position shown in Figure 4. With the bucket 11 positioned as shown in Figure 4, in other words, with the cutting edge disposed downward and toward the rear of the tractor, spreading of the material may be easily accomplished. The bucket 11 may then be returned to the digging position by a contraction of a hydraulic ram 16.

Thus it can be seen from the described mode of operation of the present invention, that the enumerated functions may be easily accomplished, with the shovel 11 of the loader under the positive control of the loader operator at all times.

Having described the invention what is considered new and desired to be protected by Letters Patent is:

- 40 1. In a loader, a boom pivotally mounted at the rear thereof on said loader, a bucket comprising a cutting edge and a vertically disposed flange mounted on the rear thereof, mounting means pivotally mounting the forward end of said boom to the lower end of said flange on said bucket, a mounting bracket fixedly mounted on said boom intermediate the ends thereof, a hydraulic ram pivotally connected to said mounting bracket and said loader for raising and lowering said boom, a lever pivotally connected to said mounting bracket to depend below the intermediate portion of said boom, a link pivotally connecting said lever with the upper end of said flange on the rear of said bucket at a point rearwardly of the means pivotally mounting said boom to said flange when said cutting edge is horizontally disposed at ground level, and a second hydraulic ram pivotally mounted between said lever and said loader for varying the degree of tilt of said bucket relative to said boom, the pivotal mounting of said second hydraulic ram to said loader being positioned rearwardly and above the pivotal connection of said boom to said loader, said second hydraulic ram, said lever and said link being formed relative to the pivot axes of said boom, said second hydraulic ram, said lever and said link so that said cutting edge is tilted rearwardly when said boom is initially raised, tilted forwardly when said boom is raised above the eye level of the operator, and tilted downwardly and rearwardly of a vertical plane through the pivot axis of said boom to said flange when said second hydraulic ram is extended and said cutting edge is at ground level.
- 45 2. In a loader, a boom pivotally mounted at the rear thereof on said loader, a bucket comprising a cutting edge, mounting means pivotally mounting the forward end of said boom to the lower rear portion of said bucket, a mounting bracket fixedly mounted on said boom inter-

mediate the ends thereof, a hydraulic ram pivotally connected to said mounting bracket and said loader for raising and lowering said boom, a lever pivotally connected to said mounting bracket to depend below the intermediate portion of said boom, a link pivotally connecting said lever with the upper rear portion of said bucket at a point rearwardly of the means pivotally mounting said boom to said bucket, and a second hydraulic ram pivotally mounted between said lever and said loader for varying the degree of tilt of said bucket relative to said boom, the pivotal mounting of said second hydraulic ram to said loader being positioned rearwardly and above the pivotal connection of said boom to said loader, said second hydraulic ram, said lever and said link being formed relative to the pivot axes of said boom, said second hydraulic ram, said lever and said link so that said cutting edge is tilted rearwardly when said boom is initially raised, tilted forwardly when said boom is raised above the eye level of the operator, and tilted downwardly and rearwardly of a vertical plane through the pivot axis of said boom to said bucket when said second hydraulic ram is extended and said cutting edge is at ground level.

3. In a loader, a boom pivotally mounted at the rear thereof on said loader, a bucket comprising a cutting edge and having a vertically disposed flange mounted on the rear thereof, mounting means pivotally mounting the forward end of said boom to the lower end of said flange on said bucket, an L-shaped mounting bracket fixedly mounted on said boom intermediate the ends thereof, said L-shaped mounting bracket positioned so that one leg thereof lies transversely of the length of said boom and the other leg thereof lies substantially parallel to the length of said boom above said boom, a hydraulic ram pivotally connected to the lower end of said transverse leg of said L-shaped mounting bracket and said loader for raising and lowering said boom, a lever, one end of said lever pivotally mounted to the end of said parallel leg of said bracket with the other end of said lever depending below the intermediate portion of said boom, a link, said link pivotally mounted between the other end of said lever and the upper end of said flange on the rear of said bucket at a point rearwardly of the means pivotally mounting said boom to said flange when said cutting edge is horizontally disposed at ground level, and a second hydraulic ram pivotally mounted between said loader and said lever intermediate the ends thereof for varying the degree of tilt of said bucket relative to said boom, the pivotal mounting of said second hydraulic ram to said loader being positioned rearwardly and above the pivotal connection of said boom to said loader, said second hydraulic ram, said lever and said link being formed relative to the pivot axes of said boom, said sec-

ond hydraulic ram, said lever and said link so that said cutting edge is tilted rearwardly when said boom is initially raised, tilted forwardly when said boom is raised above the eye level of the operator, and tilted downwardly and rearwardly of a vertical plane through the pivot axis of said boom to said flange when said second hydraulic ram is extended and said cutting edge is at ground level.

4. In a loader, a boom pivotally mounted at the rear thereof on said loader substantially at the top of said loader, a bucket comprising a cutting edge and having a vertically disposed flange mounted on the rear thereof, mounting means pivotally mounting the forward end of said boom to the lower end of said flange on said bucket, an L-shaped mounting bracket fixedly mounted on said boom intermediate the ends thereof, said L-shaped mounting bracket positioned so that one leg thereof lies transversely of the length of said boom and the other leg thereof lies substantially parallel to the length of said boom above said boom, a hydraulic ram pivotally connected to the lower end of said transverse leg of said L-shaped mounting bracket and said loader for raising and lowering said boom, a lever, one end of said lever pivotally mounted to the end of said parallel leg of said bracket with the other end of said lever depending below the intermediate portion of said boom, a link, said link pivotally mounted between the other end of said lever and the upper end of said flange on the rear of said bucket at a point rearwardly of the means pivotally mounting said boom to said flange when said cutting edge is horizontally disposed at ground level, a second hydraulic ram pivotally mounted between said loader and said lever intermediate the ends thereof for varying the degree of tilt of said bucket relative to said boom, the pivotal mounting of said second hydraulic ram to said loader being positioned rearwardly and above the pivotal connection of said boom to said loader, said second hydraulic ram, said lever and said link being formed relative to the pivot axes of said boom, said second hydraulic ram, said lever and said link so that said cutting edge is tilted rearwardly when said boom is raised above the eye level of the operator, and tilted downwardly and rearwardly of a vertical plane through the pivot axis of said boom to said flange when said second hydraulic ram is extended and said cutting edge is at ground level.
